UNITED STATES PATENT OFFICE.

JAMES FRASER, OF DUNDEE, SCOTLAND, ASSIGNOR TO THE FRASER AUTOMATIC ROVE-STOP COMPANY, LIMITED, OF DUNDEE, SCOTLAND.

ROVE-STOP MECHANISM.

SPECIFICATION forming part of Letters Patent No. 695,100, dated March 11, 1902.

Application filed June 29, 1901. Serial No. 66,499. (No model.)

To all whom it may concern:

Be it known that I, JAMES FRASER, late mill manager, a subject of the King of Great Britain and Ireland, residing at Dundee, For- 5 farshire, Scotland, have invented certain new and useful Improvements in Rove-Stop Mechanism, (for which applications for patents have been made in Great Britain, No. 3,519, dated the 19th of February, 1901, and No. 10 7,588, dated the 13th of April, 1901,) of which the following is a specification.

The objects of the invention are improvements in rove-stop mechanism for spinning-machines; and it consists, essentially, in the 15 use, in combination with a hackle-gill, of a tumbling or throwing-out weighted or spring-actuated lever supported in normal working position by a horizontal trigger-rod and lever-fittings for throwing the rove or yarn to one 20 side to clear it from the grip of the retaining-rollers, and so stop delivery of the rove without stopping the rollers when it breaks on its way to the flier or other twisting mechanism, and has for its object to simplify the 25 construction of such mechanism and its application to existing machines, to increase its sensitivity and render its action more positive and efficient, and also facilitate its manipulation by the operator.

Referring to the drawings which form part 30 of this specification, Figures 1 and 2 are respectively a side sectional view and a front view, without the drawing-rollers, of parts of a spinning-machine fitted with the improved 35 rove-stop mechanism; and Fig. 3 is a side sectional view of a lighter and different construction. Fig. 4 is a section of the wedge 7 to show its shape. Fig. 5 is a plan, partly in section, of the arrangement shown in Fig. 3.

In carrying the said improvements as illustrated by Figs. 1 and 2 into effect or practice the weighted tumbling or throwing-out lever 1 is formed, preferably, of a single piece of metal cast or forged in such a manner that 45 from its lower end, which forms a bearing or socket 2 for its pivot-pin 3, it passes upward, first vertically, then in a backward curve behind the retaining-rollers 21 and 22, and finally to the front above them. At its latter 50 part it is preferably reduced to the form and dimensions of a thin round rod 4 for conven-

ient contact and action on the rove, and at its end the rod 4 carries a weight 5. At or about the bottom of the curved part or otherwise near where the trigger 6 finds its bearing a 55 wedge-shaped projection 7 is formed on the throw-out lever 1, having its apex directed outward and away from such bearing side, said wedge having one face prepared for the point of the trigger 6 to slide upon. The said bearing 60 side has also formed in or upon it a small notch or notches 8 to permanently retain the trigger 6 in the bearing or upholding position when desired or when the support of the unbroken thread 9 is not available. The oscillating lever 10, which rests for support on the thread 9 below the drawing-rollers 11 and 12 and carries the trigger 6, horizontally adjustable in the slot 24, and a rove-arresting gill 13 on its upper part, is pivoted, preferably, on the 70 same pin 3 which carries the throw-out lever 1 and which is bent at right angles horizontally and reverted for this purpose. This pivot 3 is carried by a light metal frame or plate 14, on whose upper portion a projection 75 or lug 15 is formed for receiving a set-screw 16 to act as the support for the throw-out lever 1 on the side opposite to the trigger 6 and to provide for the lever's ready and nice adjustment in the balanced or vertical working 80 position. Two such bearing plates or frames 14 for adjacent rove-stops may be mounted with suitable slot-and-screw horizontal adjustments 17 on one principal plate or frame 23, which in its turn is provided with corre- 85 sponding means for its attachment with vertical adjustment on the stud 18 on the spinning-machine. To facilitate the action of the throw-out lever by lessening the bearing angle of the rove thereupon, as also to sim- 90 plify the replacing of the rove after the action of the mechanism, the operation of threading such rove through the usual reciprocating bar 19 above the retaining-rollers 21 and 22 is dispensed with and instead short 95 rods or arms 20 are mounted thereon, having ram's-horn loops for the rove or thread at their outer or upper ends.

The action of the improved mechanism is as follows: When the yarn or thread 9 breaks 100 and ceases to support the lower end of the oscillating lever 10, the latter moves by grav-

ity back on its pivot 3 to the position shown in dotted lines and marked *a* in Fig. 1 and brings forward the trigger 6 and the rove-arresting gill 13 on its upper part above such 5 pivot. The trigger's support being thus withdrawn from the throw-out lever 1, the latter immediately falls to one side with rapidly-increasing leverage force to the position shown in dotted lines and marked *a* in Fig. 2 and 10 pushes or withdraws the rove out from between the rollers 21 and 22. In so falling the wedge-shaped projection 7, before described, impinges on the now free point of the trigger 6 to force it still farther forward, and thus 15 impel the attached rove-arresting gill 13 positively and forcibly forward into the released rove to prevent it being pulled down by the drawing-rollers 11 and 12. The rove is thus automatically but positively stopped until 20 the broken end is repaired at the operator's leisure. To readjust the mechanism and effect such repair, the operator simply pulls forward the lower end of the oscillating lever 10 to the position shown in dotted lines 25 and marked *b* in Fig. 1, when the trigger 6 at its upper end first presses on the wedge-piece 7, so as to fully raise the throw-out lever 1, and then falls into the side notch 8, which retains it in that position and leaves the operator's hands free. The loose rove being rolled 30 back, reentered between the retaining and drawing rollers, and "pieced" together in the known way, the mechanism is then simply set by pushing back the lower end of the oscillating lever 10 until it is supported by the 35 running thread and is in turn supporting the rove-lever 1 by means of the trigger 6, simultaneously freed from its notch 8. It is to be noted that as the result of the present im- 40 provements no further addition to the usual piecing operation is required beyond the pushing backward or forward of the lower end of the oscillating lever 10.

Fig. 3 illustrates a construction suitable 45 for machines where an appliance of lighter construction is more suitable and which dispenses with the wedge-piece 7 and in which a twisted or corrugated wire spring 8^x is secured vertically on the frame for the purpose 50 of retaining the horizontal trigger 6 in position when the rove is being pieced and re-entered after a break instead of the notches 8, (shown in Figs. 1 and 2,) so that when the oscillating lever 10 is pulled forward at its 55 lower end past its normal working position the trigger part at the top end is caught between the corrugations and held securely, so as to leave the operator's hands both free, and is instantly released after replacing the throw- 60 out lever by the setting of the oscillating lever in its normal working position. In this construction the eyes of the levers 1 and 10, which oscillate on the pivot-pin 3, are preferably formed by coiling the wire of which the 65 levers are made around a short tube or sleeve. The action is similar to that described. The unbroken thread 9, bearing on the bent end

of the lever 10, upholds the throwing-out lever 1 by means of the trigger 6 bearing on its side. When the thread breaks, the lever 10 falls into the position shown in dotted lines and marked *a* and the hackle-gill moves forward and engages with the rove, while the lever 1 falls to one side and pushes the rove out from between the retaining-rollers 21 and 22. The piecing and reentering of the rove is effected as already described. 70 75

Having now described my invention, what I claim, and desire to secure by Letters Patent, is— 80

1. A rove-stop mechanism for spinning-machines consisting of a weighted throw-out lever, an oscillating vertical lever, a sustaining and releasing horizontal trigger-rod and a hackle-gill on the upper end of said oscillating vertical lever substantially as herein set forth. 85

2. Rove-stop mechanism for spinning-machines consisting of a weighted tumbling throwing-out lever formed with an angled projection and provided with means for nice adjustment in normal working position, a sustaining and releasing horizontal trigger-rod and means for sustaining same while the broken yarn is being pieced and a hackle-gill 95 both on the upper part of a vertical oscillating lever all mounted on the machine-frame and horizontally and vertically adjustable thereon substantially as herein set forth. 100

3. In rove-stop mechanism for spinning-machines and in combination, a weighted throw-out lever having sustaining devices, an oscillating lever 10 to engage the rove, said lever carrying a horizontal trigger to engage the sustaining devices, the hackle-gill carried on the upper end of the oscillating lever, a plate 14 carrying the pivot for the throw-out lever, a set-screw 16 carried by said plate to act as a lateral support for the throw-out lever, said plate being adjustable horizontally and a plate 23 carrying the plate 14, said plate 23 being vertically adjustable, substantially as described. 105 110

4. In rove-stop mechanism for spinning-machines the combination of the weighted tumbling throwing-out lever 1 formed with the angled projection 7, with the horizontal trigger-rod 6, the hackle-gill 13 and oscillating lever 10 substantially as herein set forth. 115

5. In rove-stop mechanism for spinning-machines the adjustable devices for carrying the mechanism consisting of the plate 23, the slotted plates 14 and pinching-screws 17, the lugs or projections 15 and set-screws 16 for the nice adjustment of the levers 1 substantially as herein set forth. 120 125

In testimony whereof I have signed my name to this specification in the presence of two subscribing witnesses.

JAMES FRASER.
